CLAIM

The ornamental design for cosmetic applicator, as shown and described.

DESCRIPTION

FIG. 1 is a top front perspective view of the cosmetic applicator;

FIG. 2 is a left side view thereof;

FIG. 3 is a right side view thereof;

FIG. 4 is a top view thereof;

FIG. 5 is a bottom view thereof;

FIG. 6 is a front view thereof; and,

FIG. 7 is a rear view thereof.

The broken lines are included for the purpose of illustrating environmental structure and form no part of the claimed design.
